UNITED STATES PATENT OFFICE.

RICHARD GRIFFITHS, OF CHICAGO, ILLINOIS.

VICE.

SPECIFICATION forming part of Letters Patent No. 550,388, dated November 26, 1895.

Application filed August 3, 1895. Serial No. 558,141. (No model.)

To all whom it may concern:

Be it known that I, RICHARD GRIFFITHS, residing at Chicago, in the county of Cook and State of Illinois, have invented certain new and useful Improvements in Vises, of which the following is a specification, reference being had therein to the accompanying drawings.

This invention relates to bench-vises especially intended for woodworkers' use, but capable of use by metal-workers and for analogous purposes.

The object of the invention is to produce a vise in which the clamping-jaw may be opened to any desirable width within the capacity of the vise by a quick sliding movement, and from this open position closed slightly by a turn of the same lever or handle which is used in all the manipulations, and to generally improve the construction and operation of vises of this class.

Figure 1 is a central longitudinal section of the bench-vise with some parts in elevation. Fig. 2 is a bottom plan of the same with the casing partly broken away. Fig. 3 is a cross-section through the shell and locking-dog. Fig. 4 is a broken perspective detail of the locking-cam on the lever. Fig. 5 is a detail of a broken perspective detail of the cam abutment on the jaw.

The shell 1 is preferably of cast metal, nearly rectangular in general outline, and provided with lugs 2 3 at its upper corners, by which it may be bolted to the under side 35 of a work-bench. The projecting jaw 4 is preferably integral with the shell and may be notched onto the bench 5, and the overhang 6 on the top of the jaw serves to hold the shell firmly to the bench, so that the bench really 40 forms the backing of the jaw.

The shell 1 is open at the bottom, but has lugs 7 7 projecting at its sides, into which screws or bolts 8 enter to hold the bottom plate firmly to the shell.

The bottom plate 10 is a metallic plate having side lugs 11, through which screws or bolts 8 pass into lugs 7 to hold the bottom to the shell. The lugs and bolts are a convenient means of attachment; but other means might 50 be used.

The bottom plate 10 has a slot 12 extend-

ing nearly its entire length, and the plate may be strengthened by ribs or flanges 13. Ribs 14 near the front of the plate give strength and rigidity.

The inner face of bottom plate 10, between the sides of the shell 1 and at both sides of slot 12, has rack-teeth 15, extending crosswise, the perpendicular faces of these teeth being toward the rear.

The movable jaw 24 is preferably attached to slide-piece 20 by a socket-and-pin connection, as indicated in Fig. 1; but the jaw and slide-piece may be integral. The slide-piece 20 is preferably a rectangular metallic shell 65 or casting, which carries the movable jaw and slides loosely inside the shell 1. The front end of the slide-piece has a strong shoulder 21, and the rear end has a plate 22, and the spindle 30 passes through bearings in this 70 shoulder and plate. This spindle is preferably a steel rod, and can slide, as well as turn, in its bearings.

The front end or shoulder 21 of slide-piece 20 has on its outer and inner faces cam-plates or 75 screw-sections 23 and 26. The rod 30 has rigidly fixed thereto the complementary screw-sections or cam-surfaces 33 and 36. These cam-faces or screw-sections are of opposite pitch, so that if the rod or shaft 30 be secured 80 against longitudinal movement the partial rotation of said rod in one direction will press the slide-piece 20 and its jaw outward or away from jaws 4 by the engagement of inclines 33, carried by the rod, against inclines 23 on 85 the shoulder of the slide-piece; and under like conditions a reverse rocking movement of rod 30 will press the slide and jaw inward by the engagement of cams, inclines, or screw-sections 36, attached to the rod, with the complementary inclines 26 on the shoulder or end 90 of the slide-piece.

The inclines 23 and 26 on the front and rear faces of shoulder 21 do not make a complete half-turn; but there is a straight or flat face 95 23^x or 26^x, against which the extreme end of the complementary inclines 33 or 36 will bear during a small part of the rocking of bar 30, so that this rocking may take place for a limited distance without moving the jaw and 100 slide-piece either out or in.

Rod 30 may be rocked by means of the

lever or handle 31, rigidly connected thereto. Near the rear end of the rod two collars 35 and 37 are pinned or otherwise securely fastened to the rod. Between these collars there is a dog 40, having ratchet-teeth 41 at its lower end. The dog is open at the center and has an inclined shoulder 42 in position to be engaged by a pin 39 in rod 30 to lift said dog. The rocking of rod 30 in a particular position 10 lifts the teeth of dog 40 out of engagement with teeth 15 of plate 10; but normally dog 40 is pressed down by a spring 43, attached to the inside of the slide-piece and bearing on the dog. The flat places 23^X and 26^X on the 15 abutting surfaces permit such rocking of rod 30 as will cause the dog 40 to be locked to plate 10 before the engaging cams or screw-sections begin to exert longitudinal pressure on the front or rear faces of shoulder 21; 20 but when the complementary inclines engage, dog 40 being then in firm engagement with plate 10 and rod 30 being held against longitudinal movement by collars 35 or 37, engaging said dog, the shoulder 21, slide-piece, 25 and jaw will be pressed forward or backward by the engagement of the inclines, according to the direction in which the lever is turned.

To unlock the dog, lever 31 is swung to its extreme position, which moves the jaw outward to the extent of the inclines and then 30 raises the dog while the inclines 33 are passing over the flat surfaces 23^X. The dog being unlocked, the slide-piece may be quickly slid out or in to any desirable distance with 35 in the scope of the machine by drawing on lever or handle. When the jaw is at approximately the right position, lever 31 is turned downward, as generally constructed, and rod 30 is rocked, permitting spring 43 to first lock 40 the dog, and then the engagement of the incline presses the jaw forward with great force.

The bolt or retaining-head 50, below the bottom plate, is connected by a stem 51, passing through the slot in said bottom plate, to 45 the sliding piece, preferably at the inner end thereof, as shown. The sliding piece is thus

guided and prevented from lifting at its rear end.

I have described the device in the best form known to me; but modifications may be made 50 within the scope of the claims without departing from my invention.

What I claim is—

1. In a vise of the character described, the metallic shell having a fixed jaw attached, 55 the removable bottom plate of such shell having a longitudinal slot and transverse rack teeth, and the sliding piece carrying the movable jaw and having a dog with teeth thereon in position to engage said rack teeth, a retaining head on the sliding piece passing through the said slot, and means for engaging and disengaging the dog with the rack teeth, all combined substantially as described.

2. In a vise of the character described, the 60 shell having a rack with which the dog may engage and the sliding piece in said shell, the jaws carried by said parts, and the rock shaft having inclines engaging said sliding piece as described, and the dog operated in one direction by the rock shaft and the other by a spring, all combined substantially as described.

3. In a vise of the character described, the shell having rack teeth with which the dog 75 may engage and having a fixed jaw, the sliding piece and movable jaw, the rock shaft carried by the sliding piece and having inclines to bear against inclines on the sliding piece, 80 one of said engaging parts having plane faces adjacent to the inclines, and the locking dog actuated by the rock shaft while said plane faces are in contact with the corresponding projections on the other bearing part, all substantially as described.

In testimony whereof I affix my signature in presence of two witnesses.

RICHARD GRIFFITHS.
